UNITED STATES PATENT OFFICE.

JAMES ROBB, OF LEWISTOWN, PENNSYLVANIA.

IMPROVEMENT IN PLOW-FASTENING DEVICES.

Specification forming part of Letters Patent No. 9,332, dated October 12, 1852.

To all whom it may concern:

Be it known that I, JAMES ROBB, of Lewistown, in the county of Mifflin and State of Pennsylvania, have invented certain new and useful Improvements in Plows; and I do hereby declare that the following is a full, clear, and exact description of the same, reference being had to the accompanying drawings, forming a part of this specification, in which—

Figure 1 is a perspective view of the plow. Fig. 2 is a side view, looking toward the interior of the mold-board, with the landside, reversible share, wedge F, and colter removed, the position of the bar-point being seen in red lines. Fig. 3 is an interior side view of the landside detached; Fig. 4, an inverted plan or under view of a portion of the plow; Fig. 5, a similar view, showing the reversible share E removed; Fig. 6, a detached face view of the share, and Fig. 7 a perspective view of the wedge F.

The same letters of reference denote corresponding parts throughout the several figures.

A is the landside of the plow. It consists of a plain plate of cast or wrought iron, with a projecting point-flange, a, on its interior surface; also, a stud, b, and hook c on the same side. This stud and hook, when the landside is fitted to the plow, drop into recesses d e, made in a projecting interior flange, B, of the mold-board C, against which flange the landside sits, and is held by the hook c hooking within the edge or lip of the recess e, and is further held by the reversible bar-point D, when driven to its place, as will be hereinafter described. The flange B projects, so as to form a recess or groove, f, between it and the mold-board, and the said flange at its lower and front extremity is provided with a lip, g, bending inward, and stud h, projecting also inward.

The mold-board, on its lower edge and at that part forming the opposite side of the groove f to the flange B, has headed or lipped studs i i, for holding on the reversible share E, which is further held by a tightening-wedge, F, having a lip, m.

The reversible share has holes in it for the entrance through of the studs i i and an open-

ing, r, from which shoot branches n, for the passage of the lip m through and its bite over the under face of the share.

D is the bar-point, which is of any desirable length and sharp at both ends. It also is made with notches on either side, any one of which notches is designed to receive the lip g, so that the bar-point may be reversed or, as it wears, placed farther in advance.

H is the colter or cutter. It is held between the mold-board and landside, which act as clamps to secure it. It also may be reversed to provide against wear.

To put these several parts together the landside A is fitted to the flange B of the mold-board by inserting the hook c into the recess e, the colter being dropped in its place between the landside and mold-board. The bar-point D is then slid along the groove f, it bearing on its lower side or face within and against the point-flange a and stud h, thereby retaining and tightening the landside to its hooked attachment in the recess e. When the bar-point is at its proper position along the groove f it is pressed in toward the flange B, so that one of the notches on its side will be made to receive the lip g, which prevents the bar-point from being forced out of place when set. The wedge F is next placed in the groove f alongside the bar-point, and so that the opening r and either one of the branches n (according to which side of the share is uppermost) of the share E will receive therethrough the lip m, the share being seated to the mold-board by the studs i i entering through openings in the former, the said studs being slightly headed or lipped on their end, so as to lap over the edges of the holes they pass through in the share, and, when the wedge F is driven home, serving to hold the share to the mold-board. The wedge F is then driven inward from the front till the lip m bites tight on the share by its lap over the back edge of the branch n it fits.

Now it will be seen that the landside, reversible share, and bar-point are or may be held in their place without either screw, bolt, or nut. They consequently are less liable to get loose, are firmer, and more simply put together,

and the greater the resistance on the point of the plow the tighter the wedge F will become, and the stronger or stiffer the union and attachment of the several parts together.

I do not claim, exclusively of itself, hooking the landside to the mold-board; but

What I do claim as new and useful, and desire to secure by Letters Patent, is—

Holding the share E to its place by a tight-

ening-wedge, F, having a lip, m, for lap or bite on the share, in conjunction with the headed or lipped studs; for further securing the same.

In testimony whereof I have hereunto signed my name before two subscribing witnesses.

JAMES ROBB.

Witnesses.

ALFD GREGORY,
A. E. H. JOHNSON.
